UNITED STATES PATENT OFFICE.

LUCIEN B. MARTIN, OF FOSTORIA, OHIO, ASSIGNOR TO THE FOSTORIA GLASS COMPANY.

DESIGN FOR THE ORNAMENTATION OF GLASSWARE.

SPECIFICATION forming part of Design No. 20,018, dated July 15, 1890.

Application filed May 12, 1890. Serial No. 351,421. Term of patent 7 years.

To all whom it may concern:

Be it known that I, LUCIEN B. MARTIN, a citizen of the United States, residing at Fostoria, in the county of Seneca and State of Ohio, have invented and produced a new and original Design for Glassware; and I do hereby declare the following to be a full, clear, and exact description of the same, reference being had to the accompanying illustration, forming a part thereof, and in which—

Figure 1 is a view of the design on a plane surface, or as it would appear if the article on which it is formed were flattened out. Fig. 2 is a vertical sectional view of a bowl ornamented by the design, taken on the line $x x$, Fig. 1.

The design relates to ornamental glassware; and the design consists of a series of detached figures, each representing scrolls joined at one of the curved ends to or curling in contracted form around a small circle, and the scrolls being composed of a series of depressed faces inclining from the main surface of the article.

Referring to the accompanying drawings, which represent the design when applied to a bowl A, and which bowl is in hemispherical form, having its edge portion formed into a series of scallops B, the design ornamenting the face of the article consists of a series of detached figures, each representing two scroll-like figures D and E, joined at one of the curved ends to or curling in contracted form around a small circle C. The scrolls are composed of a series of separate lines and inclined depressed faces, which lines and faces gradually move away from the circle in opposite directions, and into expanded form as they continue around it, and when of the desired width and curvature they again commence to contract until all the lines meet at a point and form the other portion of the scroll, one of the figures taking a downward direction toward the base and the other an upward direction, all the

lines of each scroll meeting at the points a and a', respectively. This scroll is preferably formed in the glass, in depression, as before stated, the outer walls b b being inclined downward, with the inner surfaces c c of the scrolls inclining upward, the effect of which inclined surfaces is to increase the number of lines forming the scrolls, and also to give to the design a distinguishing appearance. To bring out the design in glass in another and a very effective manner, the glass forming the smooth surface of the article around the scrolls may be ground, making that portion transparent, while the scrolls remain of clear glass. The scalloped rim B consists of a large and small scallop alternating around the rim of the bowl or other article, the upward scroll extending into the larger scalloped portion and having its outline to conform to that of the scallop.

While my design has been defined in decorating a bowl more particularly, yet it is obvious that it is as much applicable to any other piece of glassware—such as a pitcher, tumblers, berry-dishes, lamps, &c.—it being my intention to produce this pattern upon a full line of table-glassware.

Having now described my invention, I claim—

The design for the ornamentation of glassware, consisting of a series of detached figures, each representing scrolls joined at one of the curved ends to a curling in contracted form around a small circle, and the scrolls composed of a series of depressed faces inclining from the main surface, substantially as herein shown and described.

In testimony whereof I affix my signature in presence of two witnesses.

LUCIEN B. MARTIN.
